UNITED STATES PATENT OFFICE

2,568,322

INFANT'S TOILET SEAT

Wesley W. Cunningham, Tulsa, Okla.; Mary Louise Cunningham administratrix of said Wesley W. Cunningham, deceased

Application March 2, 1946, Serial No. 651,470

4 Claims. (Cl. 4—239)

1

There is disclosed in the following specification and the drawings accompanying the same and forming a part of this application for patent, an invention the primary purpose of which is to provide a safety attachment for toilets whereby infants may be held thereon without danger of falling in or from the toilet bowl.

Another object of the invention is to provide a false toilet seat having means whereby it may be securely attached to a common toilet seat.

This invention has for another object to provide a portable toilet seat for use of children.

A still further object of the invention is to provide a collapsible toilet seat.

The primary object of the invention, of which the accompanying drawings are illustrative, is the provision of means whereby infants may be seated upon a toilet and left there in safety while the mother or nurse may go about other duties without fear.

Other features and advantages will become more readily apparent from the following description and the accompanying illustrative drawings in which:

Figure 1 is a perspective view of the invention.

Figure 2 is a bottom plan view thereof in which the dotted lines illustrate the folded positions of the pair of arm panels forming a part of the seat,

Figure 3 is a sectional view taken on line 3—3 of Figure 2, and

Figure 4 is an elevational view of the invention shown collapsed.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10, refers to the complete invention which consists of a seat 11 formed in two sections 12 and 13 connected by hinge means comprising a pair of hinges 14

and 15 which are secured by screws to the undersurfaces 16 and 17 of said members 12 and 13. The sections 12 and 13 are provided with facing semi-cylindrical cut-outs 18 and 19 extending from the inner butting edges of the seat sections toward the outer edges thereof and which when the seat is opened up or unfolded form the cylindrical seat opening 20. Hinged to the respective outer edges 21 and 22 of the seat sections 12 and 13 are arm panels 23 and 24 which butt against the outer edges of the seat sections to extend vertically upward therefrom when the seat is unfolded for use and are foldable inward toward each other to rest against the under sides of the seat sections when the seat is folded. These arm panels are held in vertical position by straps 25 and 26 when the device is set up for use. These straps are fixed at one end 27 to one edge of an arm and attachable by a hook or button 28 to the other arm whereby an infant seated on the device will be securely penned in. As best shown in Fig. 3 of the drawings, the hinges 14 and 15, by virtue of the lateral offsets in the blades thereof, also serve to space the under sides of the seat sections 12 and 13 apart a distance at least equal to the combined thicknesses of the arm panels 23 and 24 when the seat 11 is folded, whereby the arm panels may be accommodated between the seat sections.

Adjacent the bottom rear end 29 of the seat, a rigid L-hook 30 is provided which is adapted to catch under the toilet seat 31. Preferably, this hook is in the form of an extension from one end of the pivot pintle included in the hinge 15, whereby it is rendered freely pivotal relative to the seat sections 12 and 13. Hinged to the forward under portions 32 and 33 of the seat sections 12 and 13, respectively, by means of hinges 36 and 37, respectively, are a pair of stops 34 and 35. These stops are positioned out of the paths of folding movement of the arm panels 23 and 24 and are adapted when the device is collapsed to lie flat on the surfaces 16 and 17 and when swung down vertically to maintain that vertical position for the purpose of preventing the seat 11 from any possibility of sliding forward whereby the seat 11 will be safely secured to the seat 31.

The above described device is not only adaptable for home use but because of its collapsible nature is also well adapted for use in travelling, as when folded it requires little space.

From the foregoing specification it will become apparent that the invention disclosed will adequately accomplish the functions for which it

has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after 10 considering the description in connection with the drawings. Therefore, a more lengthy description is regarded as unnecessary.

Changes in shape, size and rearrangement of details and parts such as come within the purview of the invention claimed may be resorted to, in actual practice, if desired.

What is claimed to be new is:

1. A foldable infant's toilet seat, comprising a pair of foldable seat sections having outer edges and having inner edges which are adjacent each other when said sections are unfolded, said seat sections having facing curved openings extending from the inner edges thereof toward the outer edges thereof to form a seat when said seat sections are unfolded, a pair of arm panels, hinge means respectively hinging said arm panels to the respective seat sections along the outer edges of said seat sections so that said arm panels extend vertically upward from said seat sections when the seat is unfolded for use and are foldable inwardly toward each other to rest against the under sides of said seat sections when the seat is folded, and hinge means hinging said seat sections together along the under sides thereof and provided with means for displacing said under sides of said seat sections apart a distance at least equal to the combined thicknesses of said arm panels when said seat sections are folded toward each other with the arm panels folded against the under sides of said seat sections.

2. A foldable infant's toilet seat, comprising a pair of foldable seat sections having outer edges and having inner edges which meet when said sections are unfolded, said seat sections having facing curved openings extending from the inner edges thereof toward the outer edges thereof to form a seat when said seat sections are unfolded, a pair of arm panels, hinge means respectively hinging said arm panels to the respective seat sections along the lower outer edges of said seat sections so that said arm panels butt against the outer edges of said seat sections and extend vertically upward therefrom when the seat is unfolded for use and are foldable inwardly toward each other to rest against the under sides of said seat sections when the seat is folded, hinge means hinging said seat sections together along the under sides thereof provided with means for displacing said under sides of said seat sections apart a distance at least equal to the combined thicknesses of said arm panels when said seat sections are folded toward each other with the arm panels folded against the under sides of said seat sections, and strap means fixedly connected to one of said arm panels and detachably connectible with the other of said panels for retaining said arm panels in vertically upright positions and for restraining an occupant of the seat against leaving the seat when the seat is occupied.

3. A foldable infant's toilet seat, comprising a pair of foldable seat sections having outer edges 75

and having inner edges which meet when said sections are unfolded, said seat sections having facing curved openings extending from the inner edges thereof toward the outer edges thereof to 5 form a seat when said seat sections are unfolded, a pair of arm panels, hinge means respectively hinging said arm panels to the respective seat sections along the lower outer edges of said seat sections so that said arm panels butt against the outer edges of said seat sections and extend vertically upward therefrom when the seat is unfolded for use and are foldable inwardly toward each other to rest against the under sides of said seat sections when the seat is folded, hinge means hinging said seat sections together along the under sides thereof and provided with means for displacing said under sides of said seat sections apart a distance at least equal to the combined thicknesses of said arm panels when said seat sections are folded toward each other with the arm panels folded against the under sides of said seat sections, and retaining means for detachably securing the seat to a toilet seat when unfolded for use, said retaining means including 20 a pair of securing elements respectively hinged to the under sides of said seat sections in positions removed from the paths of folding movement of said arm panels and adapted to be pivoted between positions against the under sides of 25 said seat sections and retaining positions angularly related to the under sides of said seat sections.

4. A foldable infant's toilet seat, comprising a pair of foldable seat sections having outer edges 35 and inner edges which meet when said sections are unfolded, said seat sections having facing curved openings extending from the inner edges thereof toward the outer edges thereof to form a seat when said seat sections are unfolded, a pair of arm panels, hinge means respectively hinging said arm panels to the respective seat sections along the lower outer edges of said seat sections so that said arm panels butt against the outer edges of said seat sections and extend 40 vertically upward therefrom when the seat is unfolded for use and are foldable inwardly toward each other to rest against the under sides of said seat sections when the seat is folded, hinge means hinging said seat sections together along the under sides thereof and including means for displacing said under sides of said seat sections apart a distance at least equal to the combined thicknesses of said arm panels when said seat sections are folded toward each other with the 45 arm panels folded against the under sides of said seat sections, retaining means for detachably securing the seat to a toilet seat when unfolded for use, said retaining means including a pair of securing elements respectively hinged to the under sides of said seat sections in positions removed from the paths of folding movement of said arm panels and adapted to be pivoted between positions against the under sides of 50 said seat sections and retaining positions angularly related to the under sides of said seat sections, and strap means fixedly connected to one of said arm panels and detachably connectible with the other of said arm panels for retaining said arm panels in vertically upright positions and for restraining an occupant of the seat against leaving the seat when the seat is occupied.

WESLEY W. CUNNINGHAM.
